UNITED STATES PATENT OFFICE

ROBERT G. WOODS, OF NEWTON, IOWA, ASSIGNOR OF ONE-HALF TO J. E. McANINCH,
LAURENCE L. BRIEREY, AND JAMES J. ENGLE, OF NEWTON, IOWA

COATING MACHINE

Application filed May 28, 1930. Serial No. 456,419.

An object of this invention is to provide an improved apparatus operable to apply coating material to the surfaces of flexible material fed therethrough.

5 A further object of the invention is to provide an improved apparatus including material feeding means operable to pass flexible material in operable relation across coating-applying means.

10 A further object of the invention is to provide improved coating-applying means in a material-coating apparatus.

15 A further object of the invention is to provide an improved adjustable mounting of coating-applying means in a material-coating apparatus.

20 A further object of the invention is to provide improved means for relative adjustment of the material feeding means and 25 the coating-applying means in a material-coating apparatus.

A further object of the invention is to provide an improved apparatus operable to successively apply coating material to opposite sides of flexible material fed therethrough.

30 A further object of the invention is to provide an improved apparatus operable to successively apply different coating materials to opposite sides of flexible material fed therethrough.

35 A further object of the invention is to provide improved adjustable means for supplying liquid coating material to the applying means of a material-coating apparatus.

40 A further object of the invention is to provide an improved adjustable relation of feeding means and coating-applying means in a material-coating apparatus, whereby 45 the apparatus may be operated to successfully coat various sizes, shapes and thicknesses of flexible materials.

50 A further object of the invention is to provide a material-coating apparatus arranged for continuous, progressive operation, which is positive and efficient in operation; relatively inexpensive of manufacture and installation; susceptible of ready adaptation and durable in use.

55 My invention consists in the construction,

Figure 1 is a front elevation of my complete apparatus as assembled ready for practical use. Figure 2 is a cross section on the indicated line 2—2 of Figure 1 on an enlarged scale relative to said latter Figure.

Figure 3 is an elevation of the right hand end of the machine or apparatus as shown in Figure 1. Figure 4 is an elevation of the left hand end of the machine or apparatus as shown in Figure 1.

Figure 5 is an elevation, on an enlarged scale, of one of the gear cases employed in my improved apparatus, the cover plate of said case being removed to disclose interior arrangement.

Figure 6 is an elevation, on the same scale as Figure 5, of a second gear case employed in the improved apparatus, the cover plate of said case being removed to disclose interior arrangement.

Figure 7 is a fragmentary, detail view, partly in section, of one end of coating-applying means employed in the improved apparatus. Figure 8 is a fragmentary, detail section on the indicated line 8—8 of Figure 7.

Figure 9 is a fragmentary, detail section transversely of one of the brush elements employed in the improved apparatus. Figure 10 is a fragmentary, detail section on the indicated line 10—10 of Figure 9.

In the construction of the improved apparatus as shown, the numeral 15 designates a base formed in any desired manner of any suitable material and adapted to be horizontally disposed on a plane surface, such as a floor, bench, or the like, for the support of my assembled apparatus, means

85 for securing said base to its supporting surface being provided in a common manner, if desired. Posts 16, four in number, are fixed at one end each to and rise perpendicularly in spaced, parallel relation from the base 15, said posts being similarly spaced in pairs transversely of said base and so arranged as to define on said base the corners of a rectangle having a length

90 95 100 in excess of its width. The posts 16 as

illustrated are provided with external screw-threads to facilitate positioning and vertical adjustment of the elements carried thereby, it being understood that said posts might well be plain and provided with suitable clamping means for the support of the other elements thereon, if so desired.

My improved apparatus comprises three distinct, unitary assemblies, namely, a feeding mechanism and two coating-applying assemblies, all of which are adapted to be carried by the base 15 and posts 16 for cooperative functioning in various combinations according to the purpose for which the apparatus is to be employed.

Considering the upper of the coating-applying assemblies illustrated, U-shaped yokes 17 are formed with registering holes in their parallel legs wherethrough a post 16 may be received to slidably mount said yokes on said posts with the bases of said yokes parallel with and spaced from said posts, one of said yokes being so mounted on each of said posts and retained in the desired position thereon by means of nuts 18 engaging above and below the yoke. The yokes 17 are positioned on the posts 16 with their bases extending inwardly and longitudinally of the base 15, thus aligning the yokes on each long side of the apparatus in parallel relation with the yokes on the other long side of the apparatus, the parallel yokes at each end of the apparatus being rigidly interconnected by means of spaced, parallel rods 19 engaging the bases of said yokes in transverse relation with the base 15. Bosses formed with horizontally-disposed apertures are provided on the parallel legs of each yoke 17 and rods 20 received in and through said bosses and securely clamped thereto connect aligned legs of said yokes on each long side of the apparatus, the assembly of elements 17, 19 and 20 thus comprising a rigid frame vertically adjustable relative to the posts 16 through manipulation of the nuts 18. Vertically-disposed in parallel relation with, adjacent and inwardly of the rods 19, cages 21 having a width less than the horizontal spacing between the rods 20 are mounted adjacent each end of the rigid frame above described by means of apertured bosses fixed to said cages and embracing the rods 19, whereby said cages are arranged for limited movement within said rigid frame transversely of the base 15; horizontally-disposed bars 22 dividing each of said cages into a plurality of uniform slide bearings parallel with the rods 19. Slide blocks 23 are arranged to slide transversely of the apparatus in the bearings defined by the cages 21 and bars 22, said blocks being preferably flanged to prevent their movement longitudinally of the apparatus, and a plurality of shafts 24 extend longitudi-

nally of the apparatus between, connect, and are journaled for rotation in corresponding slide blocks 23, said shafts 24 being similar and each provided throughout the major portion of its length with a plurality of closely spaced, toothed plates or discs 25 firmly clamped together on the shaft against spacing blocks 26. The cages 21 of the upper assembly under consideration have each five slide bearings in which seven shafts 24 are operatively positioned, the upper and lower of the slide bearings having each two such shafts.

The lower of the coating-appling assemblies is in all essential respects identical with the upper assembly above described and presents a rigid frame formed of the elements 17, 19 and 20 connected and arranged as above set forth and vertically adjustable relative to the posts 16 by means of nuts 18, the cages 21 of the lower assembly being arranged and mounted as are the cages 21 of the upper assembly and differing from said latter cages only in the number of slide bearings therein contained, there being but four such bearings in the cages of the lower assembly and five shafts 24 operatively supported by slide blocks 23 in said bearings, the lowermost bearing of the lower assembly accommodating two of said shafts.

The rods 20 extend at one end of the apparatus beyond the posts 16 to support gear cases or housings 27, 28, the gear case 27 being fixed to the rods 20 of the upper assembly and the gear case 28 supported by the rods 20 of the lower assembly, said gear cases being separate and distinct and having no direct connection one with the other. The ends of the shafts 24 adjacent the gear cases 27 and 28 are extended by means of universal joints and telescoping connections to operative connection with gears housed within said cases, all of the shafts 24 of the upper assembly connecting with gears of the case 27 and all of the shafts 24 of the lower assembly connecting with gears of the case 28. In Figure 5 is shown the gear arrangement within the case 27, the numeral 29 designating a relatively large gear journaled for free rotation substantially centrally of the case, a driven pinion 30 meshing with said gear 29 to rotate the latter. Grouped about and meshing with the gear 29 are six pinions 31, each operatively connected with a shaft 24 of the upper assembly, wherethrough the rotation of the gear 29 is transmitted to six of said shafts 24 to rotate them in a common direction, the seventh shaft 24 being connected with a pinion 32 which in turn meshes with its adjacent pinion 31, so that the two upper of the shafts 24 in the upper assembly are rotated in opposite directions. With the construction and arrangement illustrated, it

is desirable that the rotation of the pinion 30 be counterclockwise, that of the gear 29 clockwise, that of the pinions 31 counterclockwise and that of the pinion 32 clockwise, so that the two upper shafts 24 of the assembly shall be caused to turn in a downwardly feeding direction. In like manner, as shown in Figure 6, the shafts 24 of the lower assembly are connected with pinions 33 mounted for rotation within the case 28, each of said pinions 33 meshing with a gear 34 which is in turn driven by a pinion 35, which latter, together with the pinions 33, has a clockwise direction of rotation as against counterclockwise rotation of the gear 34. A drive shaft 36 is horizontally disposed longitudinally of and in spaced relation with one side of the lower assembly, which side of the apparatus will be designated hereinafter as the shaft side, and is journaled for rotation in bearings supported by brackets 37 fixed to and extending outwardly from the rods 20 of said lower assembly, suitable means, such as a belt pulley on said shaft in operative relation with a prime mover, not shown, being provided for the rotation of said shaft. The shaft 36 extends at one end beyond the outer end planes of the gear cases 27 and 28 and said projecting end is provided with a pair of similar chain sprockets 38 and 39, the sprocket 38 being directly connected by means of a chain 40 with a sprocket fixed to the outer end of the shaft supporting the pinion 30, an idler sprocket 41 being provided to permit of adjustments that may be necessary in the relation between the shaft 36 and gear case 27, so that rotation of the shaft 36 is transmitted to the pinion 30 for operation of the gears and pinions within the case 27. Since the direction of rotation of the pinion 35 is opposite to that of the pinion 30, the sprocket 39 is connected by a chain 42 with a sprocket 43 on the end of a stub shaft projecting from a supplemental housing 44 carried by the outer face of the gear case 28, the inner end of the stub shaft carrying a gear meshing with a gear on the shaft carrying the pinion 35, so that the rotation of the shaft 36 is transmitted to rotate said pinion 35 in a direction opposite to that of the shaft 36, the rotation of said shafts, naturally, being counterclockwise as viewed from the gear case end of the apparatus.

The grouping of the shafts 24 in the upper assembly is such as to form a deformed U opening away from the shaft side of the apparatus, and a shaft 45, carrying a coating-applying brush assembly hereinafter more specifically described, is positioned substantially centrally of the U formed by the shafts 24 and is supported at each end by slide blocks 23 carried in the central slide bearing of the cages 21, the end of said shaft 45 at the gear case end of the apparatus

tus extending no further than its slide block 23 while the opposite end of the shaft projects longitudinally of the apparatus beyond the posts 16 to support a chain sprocket 47 of the drive shaft 36 by means of a chain 48, the desired direction of rotation of the shaft 45 being opposite to that of the shaft 36 and necessitating the use of an idler sprocket 49, or similar device, to effect reverse rotation of said shaft 45 relative to the shaft 36. A similar shaft 45 is mounted longitudinally of the lower assembly and supported for rotation by slide blocks 23 carried by the cages 21 of said lower assembly, the end of said latter shaft away from the gear cases extending beyond the posts 16 to support a chain sprocket 50 directly connected by means of a chain 51 with a sprocket 52 on the drive shaft 36 adjacent the sprocket 47, thus providing means for driving the shaft 45 of the lower assembly in the same direction as the shaft 36. As is clearly shown in Figures 8, 9 and 10, the brush elements mounted on the shafts 45 consist of a number of similar bristle-carrying blocks 53 slidably mounted on a shaft 45 and spaced apart thereon by means of collars or shoulders 54 of less diameter than the blocks 53, discs or circular plates 55, of less diameter than the bristles carried by the blocks 53, being mounted for free rotation on and about the collars 54 between adjacent blocks 53, the whole assembly having any desired length and being firmly clamped together by means of nuts 56 engaging the shaft 45 at each end of the brush assembly. As indicated in the drawings, the bristles carried by the blocks 53 are preferably arranged in a number of separated groups radially of each block and so positioned longitudinally of said blocks as to form spirals axially of the completed brush assembly. The discs or plates 55 may be circular, as shown, or may be circumferentially notched to present a series of teeth, as indicated by dotted lines in Figure 9.

The brush elements assembled on the shafts 45 as above described have a length substantially equal to the lengths of the toothed portions of the shafts 24, and each of said brush elements or assemblies is enclosed in a housing 57 carried by the shaft 45, said housings completely enclosing the brush assemblies save for a vertically-disposed aperture longitudinally of each housing on the side adjacent the shafts 24 through which a portion of the brush periphery projects. The housings 57 may be formed of two or more parts, for convenience of manufacture and assembly, and each of said housings is formed with an offset chamber 58 extending the length of its lower portion to provide a tank or reservoir adapted to contain liquid, the floor of each

chamber 58 inclining slightly from an inlet at one end to an outlet at the other end. A pipe 59 connects the inlet end of each chamber 58 with a source of liquid supply through suitable agitators, pumps, and the like, not shown, and a vertically-adjustable overflow pipe 60 connects the outlet end of each chamber with the source of liquid supply, so that continuous circulation of liquid may be maintained through the chambers 58, the adjustment of the overflow pipe 60 relative to said chambers controlling the depth of liquid therein.

To support the weight of the housings 57 and to relieve the shafts 45 of that burden, a vertically-disposed clamp member 61 is mounted on and extends between the pair of rods 20 most nearly adjacent a housing 57 and on the side of said housing away from the aperture therein, one clamp member 61 being provided for each end of each housing. Each clamp member 61 supports a bar 62 fixed at one end thereto and extending horizontally therefrom perpendicularly to a shaft 45 outwardly of and adjacent the corresponding end of a housing 57, said bars 62 being slidably received in apertured bosses 63 fixed to or integral with the ends of the housings 57, thus providing vertical support for said housings while permitting horizontal adjustment thereof along said bars 62.

As clearly shown in Figure 2, the shafts 24 of the upper assembly are positioned between the housing 57 of that assembly and the shaft side of the apparatus, while in the lower assembly the housing 57 is positioned between the shafts 24 of that assembly and the shaft side of the apparatus, the apertures of the housings 57 in each case opening toward the adjacent shafts 24, whereby a passage is defined by and between the brush elements projecting through said apertures and the shafts 24. The four lower of the most nearly aligned shafts 24 carried by the cages of the upper assembly are adjustable at each end laterally of said cages by means of individual adjusting screws 64 engaging through side portions of the cages 21 to bear against the slide blocks 23 of said shafts, expansive coil springs 65 positioned between said slide blocks and the opposite side of the cages 21 serving to hold said blocks against said adjusting screws. In like manner, the four most nearly aligned shafts 24 of the lower assembly are arranged for independent lateral adjustment at each end relative to the cages of said assembly. The remaining shafts 24 of the apparatus and the shafts 45 are arranged for adjustment independently of the cages 21, so that, with the shafts 24 controlled by the screws 64 adjusted as desired, the cages 21 carrying said shafts may be moved toward or away from the brush elements to vary

the space between said shafts and elements, the slidable mounting of said cages on the rods 19 permitting such lateral motion of said cages which is controlled by adjusting screws 66 engaging through bases of the yokes 17 and engaging against lugs carried by each of the side portions of said cages. At the gear case end of the apparatus, adjusting screws 67 pass freely through the sides of the cages 21 and engage through arms fixed to the yokes 17 in position to bear against and control the position of the slide blocks supporting the shafts 45 and the shafts 24 most nearly adjacent the housings 57 in the lowermost slide bearings of the cages 21 of each assembly, thus permitting adjustment of these elements independently of the cages 21. At the brush drive end of the apparatus, bars 68 connect horizontally-parallel ends of the rods 20 and serve as slide bearings for members 69 between and connecting each pair of bars 68, one of said members 69 being provided for the upper and one for the lower assemblies of the apparatus, each of said members 69 being provided with an apertured boss through which is rotatably received its respective shaft 45, adjusting screws 70 engaging through arms 71 in fixed relation with the bars 68 and bearing against the members 69 serving to control the lateral position of said members 69, and consequently the position of one end of the shafts 45, independently of the cages 21, adjusting screws 72 passing freely through sides of the cages 21 at the brush drive end of the apparatus and engaging through arms 73 carried by the members 69 in position to bear against the slide blocks 23 supporting the shafts 24 most nearly adjacent the housings 57 in the lowermost slide bearings of the cages 21, serving to control the lateral adjustment of this end of said shafts and subjecting said shafts to control by the screws 70, while permitting independent adjustment thereof.

As illustrated, similar, curved arms 74 are removably and replaceably secured to and curve upwardly and forwardly from upper portions of the cages 21 of the upper assembly, the lower ends of said arms 74 engaging the forward ends of the shafts 24 in the upper slide bearing of said cages to position said shaft relative to said arms. A plurality of feeding rolls identical with or similar to the assemblies 24, 25, 26, indicated at 75, are journaled for rotation in and extend in parallel relation with the shafts 24 between the arms 74, the ends of said rolls extending at the gear case end of the apparatus beyond their supporting arm 74 and being provided with chain sprockets 76 interconnected by means of a chain 77 in driving relation with a sprocket carried by the shaft 24 engaged by the ends of the arms 130

74, so that the rolls 75 are driven in the same direction as said shaft, which is clockwise as viewed from the gear case end of the apparatus, an idler 78 being provided to 5 control the tension of the chain 77. Suitable strips 79 are provided to connect the arms 74 between the rolls 75 and form a bed over which material may be fed.

Arms 80 removably and replaceably carried by the cages 21 of the upper assembly in spaced, parallel relation above and rearwardly of the arms 74 adjustably and yieldingly support a curved bed 81 in uniformly spaced relation with and above the bed 15 formed by the rolls 75 and strips 79. The connection between the arms 80 and bed 81 is effected by means of bolts rising from said bed and passing loosely through the arms 80, nuts on said bolts preventing motion 20 thereof in one direction and providing for adjustment while expansive coil springs yieldingly urge said bed to the limit of its spacing relative to the arms 80. The bed 81 is longitudinally slotted opposite to the 25 rolls 75 and idler rolls 82 are rotatably carried by said bed in spaced parallelism with the rolls 75, thereby defining a throat between the rolls 75 and 82 through which material may be fed by the action of the rolls 30 75. The lower end of the bed 81 is extended downwardly between the cages 21 in the form of arms which engage the slide blocks 23 carrying the rearmost of the shafts 24 in the upper slide bearing of said cages, thus 35 providing that as the bed 81 is adjusted towards or away from the rolls 75 the spacing between the shafts 24 in the upper slide bearing will be varied accordingly.

In the practical operation of my improvement, the elements being assembled and arranged as illustrated and above described, it is obvious that flexible material fed between the rolls 75 and 82 will be drawn downwardly through the passage thereby defined and 45 drawn by the roll shafts 24 across the periphery of the brush element projecting through the aperture of its housing 57, which brush element, dipping in the liquid carried by the housing 57, thoroughly coats one side 50 of the material, the rate of rotation of the brush element preferably being in excess of that of the shafts 24 so that an efficient wiping action of said brush is had on the surface of the material, the discs or plates 55, being 55 free to rotate independently of the brush speed, serving to spread and hold the material against the roll shafts 24 without hastening the rate of travel of such material. After the material has passed the first brush 60 element it is directed downwardly into the lower assembly where its uncoated side is subjected to the action of the second brush element and thereby coated with the same or different liquid as has been previously applied to the first surface, the coated mate- 65

rial thence being discharged to a suitable conveyor, not shown, for further handling, treatment or disposition.

It is obvious that provision is made in the apparatus for the various adjustments 70 which may be required for coating materials of different sizes, thicknesses, degrees of flexibility and shapes, and that, if it is desired to coat but one side of the material, the lower assembly may be lowered on the posts 16 to 75 permit insertion of a conveyor under the upper assembly, or that, the lower assembly may be lowered sufficiently for mounting of the feeding assembly directly thereon, thus providing an apparatus adaptable to a wide 80 variety of usefulness in various fields.

Since infinite changes and modifications in the specific form and relation of the elements of my improvement may be had without departing from the spirit of the invention, I wish to be understood as being limited solely by the scope of the appended claims rather than by the illustrative showing and foregoing description.

I claim as my invention—

1. An apparatus of the character described comprising a base, posts rising in spaced parallel relation from said base, similar material-coating assemblies in superposed relation carried by and independently adjustable vertically of said posts, each of said assemblies comprising a plurality of feeding rolls defining a passage about and adjacent one side of a rotatable brush element, and material feeding means on and in operative relation with the upper of said assemblies.

2. An apparatus of the character described comprising a base, posts rising in spaced parallel relation from said base, similar material-coating assemblies carried in superposed relation by and independently adjustable vertically of said posts, each of said assemblies comprising a rigid frame, a rotatable brush element shiftable laterally of said frame and a plurality of feeding rolls arranged for independent lateral adjustment in said frame and defining a passage about and adjacent one side of said brush element.

3. An apparatus of the character described comprising a base, posts rising in spaced parallel relation from said base, similar material-coating assemblies carried in superposed relation by and independently adjustable vertically of said posts, each of said assemblies comprising a rigid frame, a rotatable brush element shiftable laterally of said frame, a plurality of feeding rolls arranged for independent lateral adjustment in said frame and defining a passage about and adjacent one side of said brush element, and means for simultaneously shifting a group of said feeding rolls laterally of said

frame to vary the spacing between said rolls and brush element.

4. An apparatus of the character described comprising a base, posts rising in spaced parallel relation from said base, similar material-coating assemblies carried in superposed relation by and independently adjustable vertically of said posts, each of said assemblies comprising a rigid frame, a 10 rotatable brush element shiftable laterally of said frame, a housing substantially enclosing said brush element and arranged to expose one side of said brush element therethrough, means for maintaining a liquid 15 level in said housing in contact with the periphery of said brush element, a plurality of feeding rolls arranged for lateral adjustment in said frame and defining a passage about and adjacent the exposed side of 20 said brush element, and means for rotating said feeding rolls and brush element.

5. An apparatus of the character described comprising a base, posts rising in spaced parallel relation from said base, similar 25 material-coating assemblies carried in superposed relation by and independently adjustable vertically of said posts, each of said assemblies comprising a rigid frame, a rotatable brush element shiftable laterally of said 30 frame, a housing substantially enclosing said brush element and arranged to expose one side of said brush element therethrough, means for maintaining a liquid level in said housing in contact with the periphery of 35 said brush element, a plurality of feeding rolls arranged for lateral adjustment in said frame and defining a passage about and adjacent the exposed side of said brush element, the exposed sides of said brush elements facing opposite sides of their respective 40 frames, and means for rotating said feeding rolls and brush elements.

6. An apparatus of the character described comprising a base, posts rising in spaced 45 parallel relation from said base, similar material-coating assemblies carried in superposed relation by and independently adjustable vertically of said posts, each of said assemblies comprising a rigid frame, cages 50 adjacent each end of said frame and shiftable laterally thereof, a rotatable brush element shiftable laterally of said frame independently of said cages, a plurality of feeding rolls mounted for lateral adjustment 55 in and relative to said cages, said rolls defining a passage about and adjacent one side of said brush element, and means for rotating said feeding rolls and brush element.

7. An apparatus of the character described 60 comprising a base, posts rising in spaced parallel relation from said base, similar material-coating assemblies carried in superposed relation by and independently adjustable vertically of said posts, each of said 65 assemblies comprising a rigid frame, cages

adjacent each end and shiftable laterally of said frame, a rotatable brush element shiftable laterally of said frame independently of said cages, a housing substantially enclosing said brush element, shiftable therewith, and arranged to expose one side of said element therethrough, a plurality of feeding rolls carried by said cages in position to define a passage about and adjacent the exposed side of said brush element, some of said rolls being arranged for independent adjustment in and relative to said cages and others of said rolls being arranged for adjustment independently of said cages, and means for rotating said brush element and feeding rolls.

8. An apparatus of the character described comprising a base, posts rising in spaced parallel relation from said base, similar material-coating assemblies carried in superposed relation by and independently adjustable vertically of said posts, each of said assemblies comprising a rigid frame, a rotatable brush element longitudinally of said frame and a plurality of rotatable feeding rolls defining a passage about and adjacent one side of said brush element, a drive shaft carried by one of said frames and operative connections between said drive shaft, brush elements and feeding rolls whereby said brush elements and feeding rolls may be rotated to feed material downwardly through the passage therebetween.

9. An apparatus of the character described comprising a base, posts rising in spaced parallel relation from said base, similar material-coating assemblies carried in superposed relation by and independently adjustable vertically of said posts, each of said assemblies comprising a rigid frame, a rotatable brush element longitudinally of said frame and a plurality of rotatable feeding rolls defining a passage about and adjacent one side of said brush element, a drive shaft carried by one of said frames and operative connections between said drive shaft, brush elements and feeding rolls whereby said brush elements may be rotated simultaneously with and at a greater speed than said feeding rolls.

10. In an apparatus of the character described having a base and posts rising in spaced parallel relation from said base, a material-coating assembly carried by and adjustable vertically of said posts, said assembly comprising a rigid frame slidably engaging said posts, means for positioning said frame relative to said posts, a rotatable brush element longitudinally of said frame, a plurality of feeding rolls parallel with and defining a passage about and adjacent one side of said brush element and means for rotating said brush element and feeding rolls to feed material downwardly through the passage therebetween.

11. In an apparatus of the character described having a base and posts rising in spaced parallel relation from said base, a material-coating assembly carried by and adjustable vertically of said posts, said assembly comprising a rigid frame slidably engaging said posts, means for adjustably positioning said frame relative to said posts, a rotatable brush element longitudinally of said frame and adjustable laterally thereof, a plurality of feeding rolls parallel with and defining a passage about and adjacent one side of said brush element, said feeding rolls being adjustable laterally of said frame independently of said brush element, and means for rotating said brush element and feeding rolls to feed material downwardly through the passage therebetween.

12. In an apparatus of the character described having a base and posts rising in spaced parallel relation from said base, a material-coating assembly carried by and adjustable vertically of said posts, said assembly comprising a rigid frame slidably engaging said posts, cages adjacent each end and shiftable laterally of said frame, means for adjustably positioning said frame relative to said posts, a rotatable brush element between said cages and shiftable laterally of said frame independently of said cages, a housing substantially enclosing said brush element, shiftable therewith, and arranged to expose one side of said brush element therethrough, a plurality of feeding rolls carried by said cages in position to define a passage about and adjacent the exposed side of said brush element, some of said rolls being arranged for independent adjustment in and relative to said cages and others of said rolls being arranged for adjustment independently of said cages, and means for rotating said brush element and feeding rolls.

13. In an apparatus of the character described having a base and posts rising in spaced parallel relation therefrom, a material-coating assembly carried by and adjustable vertically of said posts, said assembly comprising a rigid frame slidably engaging said posts, means for adjustably positioning said frame relative to said posts, a rotatable brush element longitudinally of said frame and shiftable laterally thereof, a housing substantially enclosing said brush element, shiftable therewith, and arranged to expose one side of said brush element therethrough, means for maintaining a liquid level in said housing in contact with the periphery of said brush element, a plurality of laterally shiftable feeding rolls parallel with said brush element and defining a passage about and adjacent the exposed side thereof, and means for rotating said brush element and feeding rolls to

feed material downwardly through the passage therebetween.

14. In an apparatus of the character described having a base, posts rising in spaced parallel relation from said base, a rigid frame slidably mounted for vertical adjustment on and relative to said posts and a plurality of feeding rolls longitudinally of said frame and independently adjustable laterally thereof, a rotatable brush element parallel with said rolls and cooperating therewith to define a passage therebetween, said brush element comprising a rotatable shaft, a plurality of cylindrical blocks loosely mounted on said shaft, bristles on and extending radially of said blocks, collars of less diameter than said blocks loosely on said shaft between and separating adjacent blocks, means engaging said shaft to clamp said shaft, blocks and collars into a unitary assembly and feeding plates of less diameter than the bristles of said brush element mounted for free rotation on said collars between adjacent blocks.

15. In an apparatus of the character described having a base, posts rising in spaced parallel relation from said base, a rigid frame slidably mounted for vertical adjustment on and relative to said posts and a plurality of feeding rolls longitudinally of said frame and independently adjustable laterally thereof, a rotatable brush element parallel with said rolls and cooperating therewith to define a passage therebetween, said brush element comprising a rotatable shaft, a plurality of cylindrical blocks loosely mounted on said shaft, bristles on and extending radially of said blocks, collars of less diameter than said blocks loosely on said shaft between and separating adjacent blocks, means engaging said shaft to clamp said shaft, blocks and collars into a unitary assembly, feeding plates of less diameter than the bristles of said brush element mounted for free rotation on said collars between adjacent blocks, a housing substantially enclosing said brush element and arranged to expose the side of said brush element adjacent said feeding rolls and means for maintaining a liquid level in said housing in contact with the periphery of said brush element.

In witness whereof I affix my signature.
ROBERT G. WOODS.
